OF WEST VIRGINIA.

REVERSING-VALVE.

1,331,585.

Specification of Letters Patent.

Patented Feb. 24, 1920.

Application filed August 19, 1918. Serial No. 250,435.

To all whom it may concern:

Be it known that I, HERMANN E. SCHILD, a resident of Pittsburgh, in the county of Allegheny and State of Pennsylvania, have 5 invented a new and useful Improvement in Reversing-Valves, of which the following is a specification.

This invention relates to reversing valves for regenerating and similar furnaces, such 10 as Siemens' open hearth furnaces, and similar types of refining and heating furnaces. The object of the invention is to provide a valve for reversing either the air or gas of such furnaces, which is of simple construction, 15 easy to operate, and which when used for reversing the gas prevents wasting the gas and avoids danger of explosions, and to provide a valve which is especially adapted for gas and air ports opening from below 20 so as to avoid overhead conduits.

As is well known, regenerating furnaces are provided with four regenerators or heating chambers for the air and gas, two for the air and two for the gas. Each of these 25 chambers is filled with fire brick or other refractory material, known as "checker work" which, upon becoming heated, serves as a means for heating the air or gas passing through the same and before entering 30 the furnace chamber. The air and gas are separately conducted, each through a previously heated regenerator chamber, where they become heated and thence pass to the furnace chamber, and the waste products of 35 combustion pass to the stack through the two remaining regenerator chambers and heat the checker work in the latter, thereby themselves becoming cooled. The first named set of regenerator chambers gradually 40 cools off and after a certain time it is necessary to reverse the course of the air and gas, so that the same will then enter through the newly heated regenerator chambers, and thence to the furnace chamber, 45 while the waste products of combustion pass out through the regenerators first used, thus reheating the same, and so on alternately.

Various forms of valves have heretofore been provided and suggested for reversing 50 the air and gas, such as butterfly valves and dome-shaped valves mounted either to reciprocate or oscillate. All prior forms of valves have, however, been somewhat complicated and difficult to repair or inspect,

and most of them have also been so constructed that they are not adapted to ports opening from below and also so that when reversing there was more or less wastage of gas.

The object of my invention is to provide 60 a reversing valve of simple construction and which is particularly adapted for flues opening from below. The invention comprises a valve mechanism constructed and operating as hereinafter described and claimed. 65

In the accompanying drawings, Figure 1 is a plan view of the valve mechanism, with the valves in horizontal section and showing diagrammatically the checker chambers and connecting flues; Fig. 2 is a similar view 70 showing one of the valves in plan and the other valve seat in plan; and Fig. 3 is a vertical sectional view on the line 3—3, Fig. 1.

In the drawings, the reference numerals 1, 1^a, indicate diagrammatically the checker 75 chambers for the gas and 2 and 2^a the checker chambers for the air. The chambers 1, 1^a are connected by passages 3 and 3^a to ports 4 and 4^a in the valve seats 5 and 5^a while the air chambers 2 and 2^a are connected by passages 6 and 6^a to ports 7 and 7^a in a valve seat 8. In the valve seats 5 and 5^a are a pair of gas ports 9 and 9^a connected respectively to the gas mains 10 and 10^a, and also a pair of ports 11 and 11^a connected by 80 passages 12, 12^a and 13 to the stack, not shown. The valve seat 8 is likewise provided with a port 14 connected by passage 15 to the stack. All of the valve seats named are flat and horizontal and the ports enter 90 through the same from below.

The gas reversing valve comprises a pair of members provided with flat bottom faces fitting and sliding on the seats 5 and 5^a and which members may be in the form of plates 95 but preferably in the form of water pans 16, 16^a of sufficient size to cover all of the three ports in the valve seats in all operative positions of the valve. These members 16, 16^a are mounted to oscillate about the regenerator ports 4 and 4^a and to this end the valve seats at the regenerator ports are provided with annular recesses 17, and the plates or pans 16, 16^a are provided with downwardly projecting annular flanges 18 105 fitting into said recess and forming the pivot for said members 16, 16^a. These members carry dome-shaped valve members 19, 19^a,

preferably lined with refractory material and with the edges thereof dipping below the surface of the water in the pans, and which dome-shaped members are provided 5 with chambers or passages 20, 20^a of such length as to connect the regenerator port with either the gas port or stack port, which two latter ports are located equidistant from the regenerator port so that said passages 10 direct the gas and products of combustion in the manner hereinafter described.

The valves described have a simple rotary or oscillatory movement back and forth in a horizontal plane on the valve seats 5 and 5^a. 15 In one of the positions of the valves the dome-shaped member 19 is in position to connect gas port 9 with regenerator port 4, thus directing the gas into the checker chamber 1, with the left hand side of the 20 water pan 16 covering the stack port 11, while the other dome-shaped member 19^a connects the regenerator port 4^a with stack port 11^a and with the left hand extension of the water pan 16^a covering the gas port 9^a. 25 Consequently the gas now enters the checker chamber 1 and is heated therein and thence goes to the furnace chamber, while the products of combustion pass through the checker chamber 1^a and through the other 30 valve member and thence to the stack. To reverse the gas the valves are merely moved toward the left so that the dome-shaped member 19 then connects regenerator port 4 with stack port 11, while the right hand 35 extension of the pan 16 covers the gas port 9, and the dome-shaped member 19^a connects regenerator port 4^a with the gas port 9^a, and the right hand extension of the pan 16^a covers the stack port 11^a. 40 Any suitable mechanism may be used for reversing the positions of the two valve members in unison. As shown, the two plates or pans 16 and 16^a are provided with toothed edge portions 22, 22^a, which are in 45 effect segments of worm gears, concentric with the axes of oscillation of said plates or pans, and which toothed portions are engaged by worms 23, 23^a, on opposite ends of the shaft 24 which is driven through 50 suitable reducing gearing 25 from a reversing electric motor 26. By this means the two valve members are moved in unison, in either direction, to effect the different port connections above described. It is obvious, 55 however, that various other forms of mechanism for moving the valve members may be employed.

The valve mechanism described can be used for reversing not only the gas, but, if 60 desired, can also be used for reversing the air flowing to the furnaces. To effect this, it would only be necessary to arrange the ports 7, 7^a, and 14, in the same positional relations to each other as the ports 4, 9 and 65 11, and use a valve member exactly as that

described except that the plate or water pan need not be extended so as to cover the third port.

The valve mechanism described is very simple and requires only slight power to 70 reverse it. It is admirably adapted to ports opening from below, and since the valve seats are flat and the valve members thereon have corresponding flat under surfaces and need not be lifted in passing from one position to the other, there is little danger of leakage of gas. The water cooling of the valve prevents warping and burning of the valves and valve seats so that a practical 75 gas-tight fit of the valves on their seats can be maintained. All of the parts are exposed 80 so that they can be readily inspected and also readily gotten at for repair when necessary.

I claim:

1. In reversing valve mechanism, the combination of a horizontal valve seat provided with three ports opening from below, a horizontally oscillating valve resting on and co-operating with said seat and provided with 90 a passage arranged in all positions of the valve to communicate with one of the three ports and to connect with one of the other two ports in each operative position of the valve, a water pan associated with said 95 valve, and mechanism for oscillating said valve.

2. In reversing valve mechanism, the combination of a horizontal valve seat provided with three ports opening from below, a 100 valve comprising a plate pivotally mounted to oscillate on and in contact with said seat and provided with a passage arranged in all positions of the valve to connect with one of said ports and in each of the two positions 105 of the valves to connect with one of the other two of said ports, said plate projecting on either side of said valve so as to cover the third port in either operative position of the valve, and mechanism for oscillating said 110 valve.

3. In reversing valve mechanism, the combination of a flat horizontal valve seat provided with a regenerator port, a gas port and a stack port, all opening from below, a 115 plate slidable on said valve seat and pivoted to oscillate about the regenerator port, said plate carrying a member having a passage which at all times is in communication with the regenerator port and in the two operative 120 positions of the valve is brought into communication with either the gas port or the stack port, said plate being of such size as to cover the third port in each position of the valve, and mechanism for oscillating 125 said plate.

4. In reversing valve mechanism, the combination of a flat horizontal valve seat provided with a regenerator port, a gas port and a stack port, all opening from below, a 130

water pan slidable on said valve seat and pivoted to oscillate about the regenerator port, said pan carrying a member having a passage which at all times is in communication with the regenerator port and in the two operative positions of the valve is brought into communication with either the gas port or the stack port, said pan being of such size as to cover the third port in each position of the valve, and mechanism 10 for oscillating said pan.

In testimony whereof, I have hereunto set my hand.

HERMANN E. SCHILD.

Witness:

ALICE A. TRILL.
